UNITED STATES PATENT OFFICE

RALPH MOODT, OF ROME, OHIO

DOOR FASTENER

Application filed April 11, 1928, Serial No. 269,233. Renewed April 18, 1930.

My present invention has reference to a new and novel latching means for doors for effectively holding a door in closed position, together with means for influencing the latching means to release the door to permit opening thereof.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

In the drawings:

Figure 1 is a horizontal sectional view through a pair of doors such as those employed in connection with an automobile garage to illustrate the application of my improvement thereon.

Figure 2 is a greatly enlarged sectional view approximately on the line 2—2 of Figure 1.

Figure 3 is a front elevation of the device as illustrated by Figure 2.

Figure 4 is a horizontal sectional view showing the door swung to open position and the latching element engaged by a spring catch for holding the door in such open position.

Figure 5 is an elevation of the latch and the supporting element therefor.

Figure 6 is a detail elevation showing the door in closed position.

Figure 7 is a sectional view approximately on the line 7—7 of Figure 6.

While my improvement is preferably designed for use in connection with garage doors, obviously the same is not to be re-

stricted in its useful capacity as the improvement may be successfully employed upon other types of doors and as a matter-of-fact, as a latching means for any swingable element. In Figure 1 of the drawings, the numeral 1 designates the posts upon which the doors 2—2 are hinged. The hinge posts 1 are connected, at the top thereof, by a beam or lintel 3, and on the under face of this beam or lintel there is secured a stop strip 4 for the doors. In the showing of the drawings the door 2, adjacent to its outer or free edge has bolted or otherwise secured thereon the vertical arm of an angle bracket 5. The horizontal arm of this bracket is indicated for distinction by the numeral 6. To the end of the vertical arm of the bracket there is hingedly secured, as at 7, a plate 8. The plate 8, and the horizontal arm 6 of the bracket 5 are formed with oppositely disposed lugs or bosses around which are arranged the end coils of a helical spring 9. The elements 6 and 8 are also preferably provided with clips 10 to engage with the said end coils of the spring.

On the upper face of the plate 8 there is preferably adjustably secured by means 11 an angle plate 12, whose widened and straight face is designed to contact with the inner face of the abutment strip 4 for holding the doors latched.

The outer or free end of the plate 8 is preferably provided with a depending eye 13 to which there is secured one end of a flexible element such as a chain 14, the latter being strained through an opening 15 in the door 2 and having attached to its outer or end link a pull element 16. Obviously a pull upon the flexible element from the exterior of the door will swing the plate 8 against the tension of the spring 9 to bring the cam element 12 thereon out of engagement with the strip 4 and thereby permit the free opening of the door. The spring 9 is of such strength that the plate 8 will be normally sustained in

horizontal position, or stop means may be provided for so holding the plate. The ring or hand grip on the end of the chain may likewise contact with the door for preventing the swinging of the plate 8 in its horizontal position. Also the free end of the plate is preferably curved downwardly, as at 17, so that when the door is swung to closed position the plate will glide under the strip 4 before the cam catch 12 thereon contacts with the said strip, the latter also gliding under the strip until the spring influences the same to contact with the inner edge of the said strip.

15 It will thus be seen that I have provided extremely simple, cheaply constructed and thoroughly efficient manner for latching doors when swung to closed position and likewise an extremely simple operating means for releasing the latch when the door is to be opened.

The latching means may be arranged at the top or at the sides of the door, the latter arrangement being disclosed by Figures 4 to 25 7 of the drawings. In these figures a single door is employed and is indicated by the numeral 18. This door is hinged, as at 19, to a garage or like building 20. The vertical abutment strip when in closed position, in Figure 7 of the drawings, is indicated by the numeral 21. The latch construction, in this instance, is horizontally instead of vertically arranged as previously described and the plate 21 that carries the cam element 22 is 30 hinged at a portion of its length, as at 23, to the spring carrying bracket 24 which is secured to the door. The plate 21 passes through an opening 25 in the door, the side walls provided by this opening being disposed at opposite angles. On the outer end of the plate 21 there is fixed a head member 26 which is round in plan, and this head member, when the door is swung to open position is designed to have one of its sides engaged 35 by an arched spring catch 27 that is fixed by means 28 to the outer face of the structure 20. With this arrangement the employment of the pull chain 14 is dispensed with, as the headed end of the plate which is disposed adjacent to the outer face of the door 40 serves as a means whereby the latch may be swung to unlatching position, it being, of course, understood that the head 26 is automatically engaged by the spring catch 27 45 when the door is swung to fully open position.

Having described the invention, I claim:

The combination with a structure having a hinged door closing an opening therein, and 50 an abutment strip for the door, of an angle bracket fixedly secured to the door, a plate hingedly secured to one end of the angle bracket, spring means between the plate and the second end of the angle bracket for holding the latter at a right angle with respect

to the door, a cam element adjustably secured on the plate to engage with the strip when the door is closed and means for swinging the plate to bring the cam out of such engagement when the door is to be opened, 70 and a spring clip fixed on the structure and engageable with one end of the plate for holding the door in open position.

In testimony whereof I affix my signature.

RALPH MOODT.
